Primary Examiner — Alvin A Hunter(74) *Attorney, Agent, or Firm* — Greenblum & Bernstein, P.L.C.(57) **ABSTRACT**

A golf club head includes a face portion, a crown portion, a sole portion and a hosel portion. The head includes a head body formed by a metallic material and a cover member formed by a material having a rigidity lower than that of the metallic material forming the head body. The head body includes an opening and a beam part that extends so as to intersect the opening. The opening is covered by the cover member. The beam part includes an inward bending portion that is bent so as to project inward of the head. The head body includes bent portions located at respective two end portions of the beam part.

FIG. 1

FIG. 2

FIG. 3

FIG. 4

FIG. 5

FIG. 6

FIG. 7

FIG. 8

FIG. 9

1
GOLF CLUB HEAD

The present application claims priority on Patent Application No. 2019-202065 filed in Japan on Nov. 7, 2019. The entire contents of this Japanese Patent Application are hereby incorporated by reference.

BACKGROUND OF THE INVENTION

Field of the Invention

The present disclosure relates to a golf club head.

Description of the Related Art

There has been known a head having a composite structure. JP2003-250933A (US2003/0134692A1) discloses a golf club head that includes: a head body having an opening; and a member made of a fiber reinforced plastic and covering the opening.

SUMMARY OF THE INVENTION

In a head having a composite structure, the rigidity of the head is reduced. The reduced rigidity lowers the pitch of sound at impact and shortens the duration (period of time during which a sound continues) of sound at impact. Such a head cannot attain a good sound at impact. A sound at impact is more than a matter of mere preference. The sound at impact can affect evaluation on the shot. The sound at impact can have an effect on the golf player's state of mind. Consequently, the sound at impact can influence the swing.

The present disclosure provides a head that has a composite structure and is excellent in sound at impact.

According to one aspect, a golf club head includes a face portion, a crown portion, a sole portion, and a hosel portion. The golf club head includes a head body formed by a metallic material and a cover member formed by a material having a rigidity lower than that of the metallic material forming the head body. The head body includes an opening and a beam part that extends so as to intersect the opening. The opening is covered by the cover member. The beam part includes an inward bending portion that is bent so as to project inward of the head. The head body includes bent portions located at respective two end portions of the beam part.

BRIEF DESCRIPTION OF THE DRAWINGS

FIG. 1 is a plan view of a head according to a first embodiment;

FIG. 2 is a bottom view of the head in FIG. 1;

FIG. 3 is a bottom view of a head body used in the head of FIG. 1, in other words, FIG. 3 shows a bottom view in which a cover member is removed from FIG. 2;

FIG. 4 is a cross-sectional view taken along line A-A in FIG. 3;

FIG. 5 is a cross-sectional view of a head according to a second embodiment;

FIG. 6 is a cross-sectional view of a head according to a third embodiment;

FIG. 7 is a cross-sectional view of a head according to a fourth embodiment;

FIG. 8 is a schematic diagram showing a method for measuring a Young's modulus; and

2

FIG. 9 is a diagram for illustrating a toe-heel direction and a face-back direction.

DESCRIPTION OF THE PREFERRED EMBODIMENTS

The following will describe embodiments in detail with appropriate reference to the drawings.

In the present disclosure, a reference state, a reference perpendicular plane, a face-back direction, a toe-heel direction, and an up-down direction are defined as follows. The reference state is a state where a head is placed at a predetermined lie angle and real loft angle on a horizontal plane HP. As shown in FIG. 9, in the reference state, a center line Z of a hosel hole is contained in a plane VP that is perpendicular to the horizontal plane HP. The plane VP is defined as the reference perpendicular plane. The predetermined lie angle and real loft angle are shown in a catalog of products, for example.

In the present disclosure, the toe-heel direction is the direction of an intersection line NL between the reference perpendicular plane VP and the horizontal plane HP (see FIG. 9).

In the present disclosure, the face-back direction is a direction that is perpendicular to the toe-heel direction and is parallel to the horizontal plane HP.

In the present disclosure, the up-down direction is a direction that is perpendicular to the toe-heel direction and is perpendicular to the face-back direction. In other words, the up-down direction in the present disclosure is a direction perpendicular to the horizontal plane HP.

First Embodiment

FIG. 1 is a plan view of a golf club head 2 according to the first embodiment as viewed from a crown side. FIG. 2 is a bottom view of the head 2 as viewed from a sole side. The head 2 includes a face portion 4, a crown portion 6, a sole portion 8, and a hosel portion 10. The face portion 4 includes a hitting face 4a. The hitting face 4a is the outer surface of the face portion 4. The crown portion 6 includes a crown surface 6a. The crown surface 6a is the outer surface of the crown portion 6. The sole portion 8 includes a sole surface 8a. The sole surface 8a is the outer surface of the sole portion 8. The hosel portion 10 includes a hosel hole 12. The head 2 is a wood type head.

As shown in FIG. 2, the head 2 includes a head body h1 and a cover member c1. The head 2 is formed by joining the cover member c1 to the head body h1. In the present embodiment, the cover member c1 is disposed on the sole portion 8. The cover member c1 constitutes a part of the sole surface 8a. The sole surface 8a is the outer surface of the sole portion 8.

The head body h1 is formed by joining a face member h12 to a main portion h11. The face member h12 has a cup shape as a whole. The face member h12 forms the entirety of the hitting face 4a. Furthermore, the face member h12 constitutes a part of the crown portion 6 and a part of the sole portion 8. The face member h12 is welded to the main portion h11. FIG. 1 to FIG. 3 show a boundary line k1 between the main portion h11 and the face member h12 with a two-dot chain line.

FIG. 2 shows a boundary line k2 on the sole surface 8a between the cover member c1 and the head body h1. The boundary line k2 is also the contour line of the cover member c1.

FIG. 3 is a bottom view of the head body h1 as viewed from the sole side. In other words, FIG. 3 is the bottom view of the head 2 from which the cover member c1 is removed. The head body h1 includes an opening 14. The opening 14 is a through hole disposed at a portion that constitutes the sole portion 8 of the head body h1. The opening 14 is the through hole provided in an outer shell part 20 (described later) of the head body h1.

The sole portion 8 includes a weight port 15. A weight member (not shown in drawings) can be detachably attached to the weight port 15.

FIG. 4 is a cross-sectional view taken along line A-A in FIG. 3. FIG. 4 is a cross-sectional view taken along a center line in a width direction of a first beam part 18. The head 2 includes a hollow portion 16. The head 2 is a hollow head. The inside of a circle in FIG. 4 shows an enlarged view of a part of FIG. 4.

The head body h1 includes the beam part 18 and the outer shell part 20. The outer shell part 20 is a wall that serves as a partition between inside and outside of the head 2. In other words, the outer shell part 20 is a wall that serves as a partition between the outside of the head 2 and the hollow portion 16. The outer surface of the outer shell part 20 forms the hitting face 4a, the crown surface 6a and the sole surface 8a. The beam part 18 has two ends each of which is connected to the outer shell part 20.

As shown in FIG. 3, the beam part 18 intersects the opening 14. In the planer view (FIG. 3) of the head body to which the cover member c1 is not attached, the beam part 18 can be observed inside the opening 14. When the opening 14 is provided on the sole portion 8 as in the present embodiment, the beam part 18 includes a portion located on the upper side of (above) the opening 14. The beam part 18 is located apart from the outer shell part 20. The beam part 18 extends from a first position on the outer shell part 20 to a second position on the outer shell part 20. The beam part 18 extends from a first position on a surrounding portion 33 that surrounds the opening 14 to a second position on the surrounding portion 33 surrounding the opening 14.

As shown in FIG. 3, in the present embodiment, each of the two ends of the beam part 18 is connected to an edge 14a of the opening 14. Each of a first end 181 of the beam part 18 and a second end 182 of the beam part 18 is connected to the edge 14a of the opening 14. The first end 181 of the beam part 18 is connected to a first position 141 of the edge 14a. The second end 182 of the beam part 18 is connected to a second position 142 of the edge 14a. The beam part 18 serves as a bridge that connects the first position 141 of the edge 14a of the opening 14 and the second position 142 of the edge 14a of the opening 14. Alternatively, each of the two ends of the beam part 18 does not have to be connected to the edge of the opening 14. The two ends 181 and 182 of the beam part 18 may be positioned on the inner surface of the surrounding portion 33 (outer shell part 20). That is, the beam part 18 may extend beyond the edge 14a of the opening 14 to reach the inner surface of the surrounding portion 33 such that the respective two ends 181 and 182 are located on the inner surface of the surrounding portion 33 (outer shell part 20). When the beam part 18 is positioned on the sole portion 8, the respective two ends 181 and 182 may be located on the inner surface of the sole portion 8. The two ends of the beam part 18 may be connected to respective ribs formed on the inner surface of the surrounding portion 33 (outer shell part 20).

From the viewpoint of enhancing rigidity of the entirety of the head 2, each of the two ends 181 and 182 of the beam part 18 is preferably connected to near the edge 14a of the

opening 14. From this viewpoint, each of the two ends 181 and 182 is preferably connected to the surrounding portion 33 of the opening 14, and more preferably connected to the edge 14a of the opening 14.

In the embodiment of FIG. 3, a plurality of beam parts respectively intersecting the single opening 14 are provided. The head body h1 includes a second beam part 22 that intersects the opening 14 in addition to the above-described beam part (first beam part) 18 intersecting the opening 14.

10 The head body h1 further includes a third beam part 24 that intersects the opening 14.

The first end 181 of the beam part 18 is located at a face side position relative to the second end 182 of the beam part 18. The first end 181 of the beam part 18 is located at a toe side position relative to the second end 182 of the beam part 18.

The beam part 22 has a first end 221 and a second end 222, and the first end 221 is located at a face side position relative to the second end 222. The first end 221 of the beam part 22 is located at a toe side position relative to the second end 222 of the beam part 22.

The first end 221 of the beam part 22 is located at the toe side position relative to the first end 181 of the beam part 18. The second end 222 of the beam part 22 is located at a heel side position relative to the second end 182 of the beam part 18.

The beam part 24 has a first end 241 and a second end 242, and the first end 241 is located at a back side position relative to the second end 242. The first end 241 of the beam part 24 is located at a toe side position relative to the second end 242 of the beam part 24.

The first beam part 18 and the second beam part 22 intersect with each other. The beam part 18 includes an intersection portion 183 at which the beam part 18 intersects with the beam part 22. The beam part 18 and the beam part 22 are integrated with each other at the intersection portion 183. Although the cross-sectional view shown in FIG. 4 includes the intersection portion 183, the beam part 18 has a substantially constant thickness as a whole. That is, the thickness of the beam part 18 at the intersection portion 183 is substantially the same as the thickness of other portions than the intersection portion 183 in the beam part 18. Although not shown in the drawings, the second beam part 22 also has a substantially constant thickness as a whole including the intersection portion 183. Such an intersection between beam parts enhances rigidities of these beam parts. Rigidities of beam parts can be further enhanced by intersecting beam parts with each other. The third beam part 24 does not intersect with other beam parts. The plurality of beam parts respectively intersecting the single opening 14 further enhance the rigidity of the head body h1. Note that the term "substantially constant" means variation in thickness falls within the scope of ± 0.1 mm.

The cover member c1 covers the opening 14. The cover member c1 is joined to the head body h1. The method for achieving this joining is adhesion using an adhesive.

As shown in FIG. 3, the head body h1 includes a support portion 30. The support portion 30 is a part of the outer shell part 20. The support portion 30 is a portion located between the edge 14a of the opening 14 and the boundary line k2. The support portion 30 supports the peripheral portion of the cover member c1 from inside the head 2. The surrounding portion 33 of the opening 14 is the support portion 30. The outer surface of the support portion 30 is recessed from the outer surface of the outer shell part 20 other than the support portion 30. Therefore, the support portion 30 forms a stepped-down portion at the boundary between the support

portion **30** and the outer shell part **20** surrounding the support portion **30**. The contour line of the stepped-down portion coincides with the contour line of the cover member **c1** and the boundary line **k2**. The stepped-down portion has a height that is equal to the thickness of the cover member **c1**. The stepped-down portion results in no step at the boundary like **k2** on the sole surface **8a**. The outer surface of the support portion **30** is adhered to the inner surface of the cover member **c1**. The support portion **30** is an adhered portion that is adhered to the cover member **c1**. As shown in the enlarged portion of FIG. 4, an adhesive layer **31** is formed between the support portion **30** and the cover member **c1**.

The cover member **c1** is a plate-shaped member that is three-dimensionally bent. The outer surface of the cover member **c1** forms a convex curved surface. This convex curved surface constitutes a part of the sole surface **8a**. The inner surface of the cover member **c1** forms a concave curved surface. In the present embodiment, the cover member **c1** has a substantially constant thickness. Note that the term "substantially constant" means variation in thickness falls within the scope of ± 0.1 mm. The cover member **c1** has a shape that is projected outward of the head. In the present embodiment, the cover member **c1** forms the sole portion **8**. The outer surface of the cover member **c1** forms the sole surface **8a**. Excepting a portion that is in contact with the support portion **30**, the inner surface of the cover member **c1** forms the sole inner surface **8b**.

As shown in FIG. 4, the beam part **18** is located apart from the cover member **c1**. The entirety of the beam part **18** is located apart from the cover member **c1**. The beam part **18** extends in the hollow portion **16** and is disposed apart from the cover member **c1**. As explained below, alternatively, at least a part of the beam part **18** may be in contact with the cover member **c1**.

The beam part **18** includes an inward bending portion **18a** that is bent so as to project inward of the head. In the embodiment of FIG. 4, the entirety of the beam part **18** is the inward bending portion **18a**. The beam part **18** does not include a portion that is bent so as to project outward of the head. The beam part **18** does not include a portion that extends straight along a straight line. Alternatively, a part of the beam part **18** may be the inward bending portion **18a**. A part of the beam part **18** may be bent so as to project outward of the head. A part of the beam part **18** may extend straight along a straight line.

In the embodiment of FIG. 4, the entirety of the beam part **18** is located apart from the cover member **c1**. The entirety of the inward bending portion **18a** is located apart from the cover member **c1**. Alternatively, the beam part **18** may be configured such that a part of the beam part **18** is located apart from the cover member **c1** and another part of the beam part **18** is in contact with the cover member **c1**. The beam part **18** may be configured such that a part of the inward bending portion **18a** is located apart from the cover member **c1** and another part of the inward bending portion **18a** is in contact with the cover member **c1**.

Although not shown in the drawings, the second beam part **22** is also located apart from the cover member **c1**. The beam part **22** also includes the inward bending portion. Also in the beam part **22**, the entirety of the beam part **22** is the inward bending portion. All the descriptions regarding the beam part **18** also are applicable to the second beam part **22**. All the descriptions regarding the beam part **18** are also applicable to the third beam part **24**.

As shown in the enlarged portion in FIG. 4, the head body **h1** includes a bent portion **32**. The bent portion **32** is formed at each of two end portions of the beam part **18**.

Each bent portion **32** includes a vertex **32a** on the outer side of a cross-sectional contour line **CL1**. The vertex **32a** is a point having a minimum curvature radius in the cross-sectional contour line **CL1**, or a vertex of an angle. The cross-sectional contour line **CL1** is a cross-sectional line in a specific cross section as described later.

10 In the present embodiment, the bent portion **32** is formed by the outer shell part **20** and the beam part **18**. The boundary between the outer shell part **20** and the beam part **18** is the vertex **32a**. The bent portion **32** is formed by the surrounding portion **33** and the beam part **18**. The boundary between the surrounding portion **33** and the beam part **18** is the vertex **32a**.

As shown in the enlarged portion in FIG. 4, the vertex **32a** of the bent portion **32** coincides with the end **182** of the beam part **18**. As with this structure, the vertex **32a** of the other bent portion **32** coincides with the end **181** of the beam part **18**. In each bent portion **32**, the vertex **32a** coincides with the edge **14a** of the opening **14**. Alternatively, the beam part **18** may include one or two bent portions **32**. In other words, at least one bent portion **32** is formed in the beam part **18**. That is, the beam part **18** may be bent to form the at least one bent portion **32**.

In the present embodiment, the bent portions **32** are located on respective two end portions of the inward bending portion **18a**. The inward bending portion **18a** starts at 30 one bent portion **32** and terminates at the other bent portion **32**. The vertexes **32a** of the bent portions **32** are the respective two end portions of the inward bending portion **18a**. In this embodiment, the inward bending portion **18a** can be formed by utilizing bending of the bent portions **32**. 35 As a result, an occupation proportion (proportion **Ra** described later) of the inward bending portion **18a** can be increased.

Each bent portion **32** is bent so as to project outward of the head. The vertex **32a** of each bent portion **32** is located 40 at a point (diverging point) from which the head body **h1** starts distancing itself from the cover member **c1**.

Each bent portion **32** is formed by a boundary portion between a first portion that is bent so as to project outward of the head and a second portion that is bent so as to project 45 inward of the head. By this change in projecting direction, the angle of bending of the bent portion **32** is increased. In the present embodiment, the first portion is the outer shell part **20** (support portion **30**). In the present embodiment, the second portion is the inward bending portion **18a**. Alternatively, the first portion and the second portion may be formed in the beam part **18**.

A double-pointed arrow **01** in the enlarged portion of FIG. 4 shows the angle of bending of the bent portion **32**. The bending angle **01** is measured on the cross-sectional contour line **CL1** in the specific cross section. The specific cross section means a cross section taken along a plane selected such that the bending angle **01** is the maximum. The bending angle **01** is an angle between a first straight line **L1** and a second straight line **L2**. The first straight line **L1** is a straight line passing through two points **T1** and **T2** located on one side relative to the vertex **32a**. The second straight line **L2** is a straight line passing through two points **T3** and **T4** located on the other side relative to the vertex **32a**. The point **T1** is a point that is located on the cross-sectional contour line **CL1** and has a direct distance from the vertex **32a** of 1.0 mm. The point **T2** is a point that is located on the cross-sectional contour line **CL1** and has a direct distance from the

vertex **32a** of 3.0 mm. The point **T3** is a point that is located on the cross-sectional contour line **CL1** and has a direct distance from the vertex **32a** of 1.0 mm. The point **T4** is a point that is located on the cross-sectional contour line **CL1** and has a direct distance from the vertex **32a** of 3.0 mm.

From the viewpoint of increasing the amplitude of vibration of the beam part **18**, the bending angle **θ1** is preferably greater than or equal to 1°, more preferably greater than or equal to 2°, and still more preferably greater than or equal to 5°. From the viewpoint of setting the curvature radius of the inward bending portion **18a** within a preferable range, the bending angle **θ1** is preferably less than or equal to 45°, more preferably less than or equal to 30°, and still more preferably less than or equal to 20°.

FIG. 5 is a cross-sectional view of a head **40** according to a second embodiment. FIG. 5 is the cross-sectional view corresponding to FIG. 4 in the first embodiment.

The head **40** includes a beam part **42**. FIG. 5 includes an enlarged portion that is a cross-sectional view of the beam part **42** taken along line A-A in FIG. 5. The beam part **42** includes a rib **44**. The rib **44** is formed on the inner surface of the beam part **42**. Alternatively, the rib **44** may be formed on the outer surface of the beam part **42**. The rib **44** is provided over the entirety of the beam part **42** in the longitudinal direction thereof. Further, the rib **44** includes two end portions that are continuous with respective ribs **46** formed on the inner surface of the outer shell part **20** and that are located at respective positions at which two end portions of the beam part **42** are located. Alternatively, the rib **44** may be provided on a part of the beam part **42** in the longitudinal direction. The rib **44** enhances the rigidity of the beam part **42**. Excepting the presence of the ribs **44** and **46**, the head **40** is the same as the head **2**.

FIG. 6 is a cross-sectional view of a head **50** according to a third embodiment. FIG. 6 is the cross-sectional view corresponding to FIG. 4 in the first embodiment.

The head **50** includes a beam part **52**. The beam part **52** includes a weight disposing portion **54**. The beam part **52** has a partially increased weight in the weight disposing portion **54**. The weight disposing portion **54** has a weight per unit length greater than that of other portions of the beam part **52**. The "length" in the "unit length" means the length of the beam part **52** in the longitudinal direction. In the present embodiment, the weight disposing portion **54** is formed by partially increasing the thickness of the beam part **52**. Alternatively, the weight disposing portion **54** may be formed by incorporating a weight body, for example. Excepting the presence of the weight disposing portion **54**, the head **50** is the same as the head **2**.

FIG. 7 is a cross-sectional view of a head **60** according to a fourth embodiment. FIG. 7 is the cross-sectional view corresponding to FIG. 4 in the first embodiment.

The head **60** includes a beam part **18**. The beam part **18** is the same as the beam part of the head **2** in the first embodiment. The head **60** includes a head body that is the same as the head body of the head **2**. The head **60** includes a cover member **c2**. The cover member **c2** has a shape that is different from the shape of the cover member **c1**. Excepting the shape of the cover member **c2**, the head **60** is the same as the head **2**.

The cover member **c2** has a shape that projects inward of the head. The beam part **18** is in contact with the cover member **c2**. The entirety of the beam part **18** is in contact with the cover member **c2**. The entirety of the inward bending portion **18a** is in contact with the cover member **c2**. The beam part **18** is adhered to the cover member **c2** with an adhesive.

The above-explained embodiments achieve the following advantageous effects.

The rigidity of the material of the cover member is lower than the rigidity of a metallic material of the head body. The head body is not present in the opening, and the opening is covered by the cover member. This structure tends to reduce the rigidity of the head as a whole and to lower the pitch of the sound at impact. Furthermore, this structure tends to shorten the duration (period of time during which a sound continues) of the sound at impact. Such a shortened duration sounds to golf players like a less reverberation of the sound at impact. Golf players prefer a moderately long-lasting sound at impact.

The beam part improves the sound at impact. The beam part vibrates at impact. The beam part tends to vibrate as compared with the outer shell part of the head body. This vibration of the beam part increases the duration of the sound at impact.

The two ends of the beam part are respectively connected to the head body (connected to the surrounding portion of the opening, for example). For this reason, the rigidity of the beam part is enhanced, and the vibration of the beam part is less likely to be damped. As a result, the duration of the sound at impact is increased. In addition, the enhanced rigidity of the beam part makes the sound at impact higher-pitched.

Since the beam part intersects the opening, reduction of the rigidity of the head body which otherwise occurs due to the presence of the opening is prevented. For this reason, a higher-pitched sound at impact is obtained.

In the vibration of the beam part, the beam part is bent alternately in opposite directions. The opposite directions mean a direction of bending in which the beam part is bent so as to project outward of the head and a direction of bending in which the beam part is bent so as to project inward of the head. The inward bending portion exhibits a high rigidity against a deformation that occurs when the inward bending portion is bent in the opposite direction to the original bending direction of the inward bending portion. That is, the inward bending portion has a high rigidity against a bending in which the inward bending portion is bent so as to project outward of the head. For this reason, the inward bending portion has a high rigidity against deformations that occur when the beam part is repeatedly bent in the opposite directions. As a result, the beam part including the inward bending portion achieves a higher-pitched sound at impact.

Bending deformation is likely to occur in the bent portions. The bent portions are formed on the respective two end portions of the beam part, thereby increasing the amplitude of vibration of the beam part and attaining a longer duration of the sound at impact.

When the beam part is not in contact with the cover member, the vibration of the beam part is not suppressed by the cover member, and thus is less likely to be damped. For this reason, a longer duration of the sound at impact is attained (non-contact effect).

When the beam part is in contact with the cover member, the beam part reinforces the cover member having a lower rigidity, thereby enhancing the rigidity of the cover member (see FIG. 7). As a result, the rigidity of the entirety of the head is enhanced, and a higher-pitched sound at impact is attained (contact effect).

When the beam part includes a portion that is in contact with the cover member and a portion that is not in contact with the cover member, both the above-described non-contact effect and contact effect can be simultaneously

obtained. In addition, in this case, the ratio between the non-contact effect and the contact effect can be adjusted.

When the beam part is adhered to the cover member, the cover member is further reinforced by the beam part, and thus the rigidity of the cover member is further enhanced. In addition, this structure prevents an abnormal noise that otherwise occurs when a vibrating beam part beats the cover member.

From the viewpoint of lowering the position of the center of gravity of the head, the sole portion usually has a thickness greater than that of the crown. When the opening is formed on the sole portion, a saved weight is increased because of the presence of the opening. The saved weight increases the degree of freedom in the design of the head.

In particular, when the two ends of the beam part are connected to the sole portion, the beam part adds its weight to the weight of the sole portion. Therefore, the position of the center of gravity of the head can be lowered.

The specific gravity of the material forming the cover member is preferably lower than the specific gravity of the metallic material forming the head body. In this case, a partial substitution of the head body with the cover member generates a saved weight. This saved weight contributes to increase in the degree of freedom in the design of the head.

As with the embodiment of FIG. 5, when a rib is provided on the beam part, the rigidity of the beam part is enhanced. As a result, a higher-pitched sound at impact is obtained. When this rib is connected to a rib (ribs) provided on the outer shell part of the head body, the rigidity of the beam part is further enhanced.

As with the embodiment of FIG. 6, when a weight disposing portion is provided, the weight disposing portion increases the amplitude of vibration of the beam part. For this reason, the duration (period of time during which vibration continues) of the vibration of the beam part is increased, and such a longer duration of the vibration sounds to golf players like a long-lasting reverberation of the sound at impact.

As shown with the beam part 18 and the beam part 22 in FIG. 3, each beam part may be bent in a planer view. This bending enhances the rigidity of the beam part itself. Alternatively, the beam part may extend along a straight line in the planer view. In this case, the weight of the beam part is saved, which can increase the degree of freedom in the design of the head. When the beam part is provided on the sole portion, the planer view means a bottom view of the head as viewed from the sole side. When the beam part is provided on the crown portion, the planer view means a plan view of the head as viewed from the crown side.

The position of the opening is not limited. For example, the opening may be provided on the crown portion. In this case, the two ends of the beam part are connected to the crown portion of the head body. In this case, the above-described advantageous effects are obtained except the effect brought by providing the opening on the sole portion.

A double-pointed arrow M1 in FIG. 4 shows a maximum distance between the beam part and the cover member. From the viewpoint of suppressing the occurrence of the abnormal noise caused by the vibration of the beam part, the maximum distance M1 is preferably greater than or equal to 1 mm, and more preferably greater than or equal to 2 mm. Considering preferable shapes of the cover member and the inward bending portion, the maximum distance M1 is preferably less than or equal to 5 mm, and more preferably less than or equal to 4 mm. This maximum distance M1 is the maximum

value of the distance between the beam part and the cover member. This distance is measured along the up-down direction.

5 A double-pointed arrow Wb in FIG. 3 shows a width of the beam part. From the viewpoint of the rigidity of the beam part, the width Wb is preferably greater than or equal to 2 mm, more preferably greater than or equal to 3 mm, and still more preferably greater than or equal to 5 mm. From the viewpoint of saving the weight of the beam part, the width 10 Wb is preferably less than or equal to 20 mm, more preferably less than or equal to 15 mm, and still more preferably less than or equal to 12 mm. The width Wb is measured along a direction that is perpendicular to the longitudinal direction of the beam part.

15 A double-pointed arrow Tb in FIG. 4 shows a thickness of the beam part. From the viewpoint of the rigidity of the beam part, the thickness Tb is preferably greater than or equal to 0.45 mm, more preferably greater than or equal to 0.6 mm, and still more preferably greater than or equal to 0.8 mm. 20 From the viewpoint of saving the weight of the beam part, the thickness Tb is preferably less than or equal to 2.0 mm, more preferably less than or equal to 1.5 mm, and still more preferably less than or equal to 1.2 mm. The thickness Tb is measured along a direction that is perpendicular to a lower surface 18b of the beam part.

25 For increasing the advantageous effect brought by providing the cover member c1, sizes of the cover member c1 and the opening 14 are preferably enlarged. The beam part intersects the opening 14. From this viewpoint, the beam part has a length of preferably greater than or equal to 30 mm, more preferably greater than or equal to 40 mm, and still more preferably greater than or equal to 50 mm. There is a limit in the size of the opening 14 due to restriction on the volume of the head. From this viewpoint, the length of 30 the beam part is preferably less than or equal to 100 mm, more preferably less than or equal to 90 mm, and still more preferably less than or equal to 80 mm. The length of the beam part is measured in the extending direction of the beam part which extends curvedly.

40 For enhancing the advantageous effect brought by the inward bending portion 18a, a proportion Ra (%) of the inward bending portion 18a to the beam part 18 is preferably greater. From this viewpoint, the proportion Ra is preferably greater than or equal to 70%, more preferably greater than or equal to 80%, still more preferably greater than or equal to 90%, and yet still more preferably greater than or equal to 95%. The proportion Ra may be 100%. In the embodiment of FIG. 4, the proportion Ra is 100%. The proportion Ra can be calculated by dividing the length of the inward bending portion by the length of the beam part. The length of the inward bending portion is measured along the extending direction of the inward bending portion which extends curvedly. The length of the beam part is measured as described above.

55 A lightweight cover member c1 increases the degree of freedom in the design of the head. From this viewpoint, the cover member c1 has a thickness of preferably less than or equal to 0.9 mm, more preferably less than or equal to 0.8 mm, and still more preferably less than or equal to 0.7 mm. 60 From the viewpoint of enhancing the rigidity of the cover member c1, the thickness of the cover member c1 is preferably greater than or equal to 0.2 mm, more preferably greater than or equal to 0.3 mm, and still more preferably greater than or equal to 0.4 mm.

65 The beam part 18 has a center of gravity that is located at a toe-side position relative to the position of the center of gravity of the head 2 (see FIG. 3). The beam part 18 is useful

11

in locating the center of gravity of the head at a toe-side position. Alternatively, the center of gravity of the beam part **18** may be located at a heel-side position relative to the position of the center of gravity of the head **2**.

The curvature radius of bending of the inward bending portion **18a** is not limited. From the viewpoint of enhancing the rigidity of the beam part **18**, it is not preferable that the curvature radius of the inward bending portion **18a** is excessively large or excessively small. As to the lower limit, the curvature radius is preferably greater than or equal to 38.1 mm, more preferably greater than or equal to 127 mm, and still more preferably greater than or equal to 254 mm. As to the upper limit, the curvature radius is preferably less than or equal to 2540 mm, more preferably less than or equal to 1905 mm, and still more preferably less than or equal to 1270 mm. The curvature radius is measured in a cross-sectional view taken along the center line of the beam part **18** in the width direction. The curvature radius can be a curvature radius of the cross-sectional line of the lower surface **18b** of the beam part **18**.

The material of the cover member **c1** is different from the material of the head body **h1**. The material of the cover member **c1** can be a resin material, a composite material, or a metallic material. The material of the cover member **c1** may be a combination of two or more materials selected from the group consisting of a resin material, a composite material, and a metallic material. Examples of the resin material include an epoxy resin, a polycarbonate resin, a polyamide resin, and an ABS resin (acrylonitrile butadiene styrene resin). Examples of the composite material include a fiber reinforced plastic. Examples of the fiber reinforced plastic include carbon fiber reinforced plastic. From the viewpoint of strength, the carbon fiber reinforced plastic is preferable. Examples of the metallic material include pure titanium, a titanium alloy, a steel, an aluminum alloy, and a magnesium alloy. Examples of the steel include maraging steel, stainless steel, and soft iron (a carbon steel having a carbon content of less than or equal to 0.3% by weight). When the metallic material is selected as the cover member **c1**, a metallic material having a lower rigidity than the rigidity of the metallic material of the head body is selected as the metallic material for the cover member **c1**. In the above embodiments, the material forming the cover member **c1** is carbon fiber reinforced plastic.

Examples of a metallic material forming the head body **h1** include pure titanium, a titanium alloy, a steel, an aluminum alloy, and a magnesium alloy. Examples of the steel include maraging steel, stainless steel, and soft iron (a carbon steel having a carbon content of less than or equal to 0.3% by weight). In the above embodiments, the material forming the head body **h1** is a titanium alloy. Alternatively, the head body **h1** may be formed by two or more kinds of metallic materials.

Alternatively, the head body **h1** may be formed by joining two or more metallic members to each other. The method of this joining is preferably welding.

As described above, the rigidity of the material forming the cover member **c1** is lower than the rigidity of the metallic material forming the head body **h1**. The rigidity can be determined by Young's modulus. The Young's modulus of the material forming the cover member **c1** is lower than the Young's modulus of the metallic material forming the head body **h1**.

Values of Young's moduli for commonly used materials are known. Young's moduli of the materials are compared based on the known values of Young's moduli. When the Young's modulus of a certain material is unknown, or

12

magnitude relationship between Young's moduli of materials is unclear, those Young's moduli can be specified by the following measurement method.

FIG. 8 is a schematic diagram showing a method for measuring the Young's modulus. No. 3 test piece according to bend test pieces for metallic materials in JIS 22204 is used in this measurement as a test piece **S1**. The test piece **S1** has a cross-sectional shape of a rectangle. The test piece **S1** has dimensions of 20 mm in width **W** (not shown), and 3.0 mm in thickness **T**. The test piece **S1** has a length **L** of 150 mm. The test piece **S1** is placed on two supports **P1** and **P2** arranged such that a span **Ls** between the two supports is 30 mm. The test piece **S1** is laid horizontally. A bending amount **D1** (mm) is measured when a load **F** (N) is applied to a position dividing the distance between support points **p1** and **p2** into two equal parts. The load **F** is 100 N. The load **F** is applied with an indenter **A1**. As a testing device, "Intesco (load cell 2 tons)" produced by Intesco Co., Ltd. can be used. The measurement is performed in compliance with JIS 22248. Young's modulus **Yg** (GPa) is calculated by the following formula:

$$Yg = [(Ls^3 \times F) / (4 \times W \times T^3 \times D1)] \times 10^{-3}$$

The Young's modulus of a material that cannot be measured by the above method can be measured by a flexural resonance method. In the flexural resonance method, a test piece having dimensions of 10 mm $\times$ 60 mm $\times$ 2 mm is used, and the Young's modulus can be measured at temperature of 20° C.

When the material has anisotropy, the test piece is prepared such that the Young's modulus is the maximum.

A head having a large volume and including a large hollow portion **16** has a big sound at impact. In this case, the influence of the sound at impact to the golf player is great. In addition, when the opening **14** is large, the advantageous effect brought by the beam part **18** is also great. From this viewpoint, the head **2** has a volume of preferably greater than or equal to 300 cc, more preferably greater than or equal to 350 cc, still more preferably greater than or equal to 400 cc, and yet still more preferably greater than or equal to 420 cc. From the viewpoint of golf rules, the head volume is preferably less than or equal to 470 cc, and more preferably less than or equal to 460 cc.

The following clauses are disclosed regarding the above-described embodiments.

[Clause 1]

A golf club head comprising:
 a face portion;
 a crown portion;
 a sole portion; and
 a hosel portion, wherein
 the golf club head includes a head body formed by a metallic material, and a cover member formed by a material having a rigidity lower than that of the metallic material forming the head body;

the head body includes an opening and a beam part that extends so as to intersect the opening,
 the opening is covered by the cover member,

the beam part includes an inward bending portion that is bent so as to project inward of the golf club head, and
 the head body includes bent portions located at respective two end portions of the beam part.

[Clause 2]

The golf club head according to clause 1, wherein the material forming the cover member is at least one selected from the group consisting of a resin material, a composite material, and a metallic material.

13

[Clause 3]

The golf club head according to clause 1 or 2, wherein the material forming the cover member has a specific gravity that is lower than a specific gravity of the metallic material forming the head body.

[Clause 4]

The golf club head according to clause 3, wherein the opening is formed on the sole portion.

[Clause 5]

The golf club head according to any one of clauses 1 to 4, wherein the beam part includes a portion that is located apart from the cover member.

[Clause 6]

The golf club head according to clause 5, wherein an entirety of the beam part is located apart from the cover member.

[Clause 7]

The golf club head according to any one of clauses 1 to 4, wherein the beam part includes a portion that is in contact with the cover member.

[Clause 8]

The golf club head according to clause 7, wherein an entirety of the beam part is in contact with the cover member.

[Clause 9] The golf club head according to any one of clauses 1 to 8, wherein the beam part includes a weight disposing portion formed by partially increasing weight of the beam part.

LIST OF REFERENCE NUMERALS

- 2, 40, 50, 60 Head
- 4 Face portion
- 4a Hitting face
- 6 Crown portion
- 8 Sole portion
- 10 Hosel portion
- 14 Opening
- 14a Edge of opening
- 141 First position of edge of opening
- 142 Second position of edge of opening
- 16 Hollow portion
- 18 Beam part (first beam part)
- 18a Inward bending portion
- 181 First end of beam part
- 182 Second end of beam part
- 20 Outer shell part
- 22 Beam part (second beam part)
- 24 Beam part (third beam part)
- 30 Support portion
- 32 bent portion
- c1 Cover member

The above descriptions are merely illustrative and various modifications can be made without departing from the principles of the present disclosure.

What is claimed is:

1. A golf club head comprising:
  - a face portion;
  - a crown portion;
  - a sole portion; and
  - a hosel portion, wherein
 the golf club head includes a head body formed by a metallic material, and a cover member formed by a material having a rigidity lower than a rigidity of the metallic material forming the head body,

the head body includes an opening and a beam part that extends so as to intersect the opening,

14

the opening is covered by the cover member, the beam part includes an inward bending portion that is bent so as to project inward of the golf club head, and the head body includes bent portions, located at respective two end portions of the beam part, that are each bent so as to project outward of the golf club head.

2. The golf club head according to claim 1, wherein the material forming the cover member is at least one selected from the group consisting of a resin material, a composite material, and a metallic material.

3. The golf club head according to claim 1, wherein the material forming the cover member has a specific gravity that is lower than a specific gravity of the metallic material forming the head body.

4. The golf club head according to claim 3, wherein the opening is formed on the sole portion.

5. The golf club head according to claim 1, wherein the beam part includes a portion that is located apart from the cover member.

20 6. The golf club head according to claim 5, wherein an entirety of the beam part is located apart from the cover member.

7. The golf club head according to claim 1, wherein the head body includes a surrounding portion that surrounds the opening, and the beam part extends from a first position on the surrounding portion to a second position on the surrounding portion.

8. The golf club head according to claim 7, wherein the head body includes a support portion that supports a peripheral portion of the cover member from inside the golf club head, and the surrounding portion surrounding the opening forms the support portion.

9. The golf club head according to claim 1, wherein the beam part includes a first end that is connected to a first position of an edge of the opening, and a second end that is connected to a second position of the edge of the opening.

10. The golf club head according to claim 1, wherein the bent portions are bent at an angle of greater than or equal to 1 degree and less than or equal to 45 degrees.

11. The golf club head according to claim 1, wherein the bent portions are bent at an angle of greater than or equal to 1 degree and less than or equal to 30 degrees.

45 12. The golf club head according to claim 1, wherein the beam part includes a first beam part and a second beam part intersecting the first beam part.

13. The golf club head according to claim 12, wherein the second beam part intersects the opening.

50 14. A golf club head comprising:

- a face portion;
- a crown portion;
- a sole portion; and
- a hosel portion, wherein

55 the golf club head includes a head body formed by a metallic material, and a cover member formed by a material having a rigidity lower than a rigidity of the metallic material forming the head body, the head body includes an opening and a beam part that extends so as to intersect the opening,

the opening is covered by the cover member, the beam part includes an inward bending portion that is bent so as to project inward of the golf club head, the head body includes bent portions located at respective two end portions of the beam part, and the beam part includes a portion that is in contact with the cover member.

15

15. The golf club head according to claim 14, wherein an entirety of the beam part is in contact with the cover member.

16. A golf club head comprising:

a face portion;

5

a crown portion;

a sole portion; and

a hosel portion, wherein

the golf club head includes a head body formed by a metallic material, and a cover member formed by a

material having a rigidity lower than a rigidity of the metallic material forming the head body,

the head body includes an opening and a beam part that extends so as to intersect the opening,

the opening is covered by the cover member,

the beam part includes an inward bending portion that is

bent so as to project inward of the golf club head,

the head body includes bent portions located at respective

two end portions of the beam part, and

the beam part includes a weight disposing portion formed by partially increasing weight of the beam part.

16
